FIG. 5

UNITED STATES PATENT OFFICE.

ROBERT M. GILSON, OF PITTSBURGH, PENNSYLVANIA, ASSIGNOR TO THE UNION
SWITCH & SIGNAL COMPANY, OF SWISSVALE, PENNSYLVANIA, A CORPORATION
OF PENNSYLVANIA.

SIGNAL.

1,227,777.

Specification of Letters Patent. Patented May 29, 1917.

Application filed January 20, 1914. Serial No. 813,157.

To all whom it may concern:

Be it known that I, ROBERT M. GILSON, a citizen of the United States, residing at Pittsburgh, in the county of Allegheny and 5 State of Pennsylvania, have invented certain new and useful Improvements in Signals, of which the following is a specification.

My invention relates to signals and particularly to signals of the type in which a 10 source of light is employed for giving indications both at night and in daylight. Signals embodying my invention are particularly adapted for use in railway signaling, although they are not limited to this particular adaptation. When a signal of the 15 type mentioned is used on a railway curve, the beam of light projected by the signal should be visible over all points on the curve in the rear of the signal. Hence, this beam is 20 preferably elongated in a horizontal direction, but not in a vertical direction. Furthermore, it is desirable that the beam should appear to be about of the same intensity from all points on the curve, hence the beam 25 preferably varies progressively in intensity from a maximum value adjacent one end to a minimum value adjacent the other, the more intense portion of the light being directed toward the end of the curve farthest 30 from the signal and the less intense portions being directed toward the sections of the curve nearer to the signal. One feature of my invention is the provision of a signal which will project an elongated beam of 35 light which varies progressively in intensity from the maximum value adjacent one end to a minimum value adjacent the other.

I will describe several forms of signals embodying my invention, and will then 40 point out the novel features thereof in claims.

In the accompanying drawings, Figure 1 is 45 a top view showing one form of signal embodying my invention. Fig. 2 is a view showing in front elevation the screen 12 shown in Fig. 1. Fig. 3 is a view showing on an enlarged scale a portion of the screen 12 shown in Fig. 1, and illustrating the manner in which light rays are reflected thereby. Fig. 4 is a curve showing the intensity of 50 light at the various points along the line IV—IV of Fig. 1. Fig. 5 is a view showing a railway curve provided with a signal embodying my invention, and indicating the portions of the curve toward which are di- 55 rected the several parts of the beam indicated by the zones in Fig. 3.

Similar reference characters refer to similar parts in each of the several views.

Referring first to Figs. 1, 2 and 3, the signal here shown comprises an incandescent 60 lamp 10 from which a beam of light comprising substantially parallel rays 13 is projected by a lens 11. Although I have shown an incandescent lamp as the source of light, it is understood that any other suitable 65 source may be employed; and although I have shown a lens, it is understood that any other suitable means may be employed for projecting a beam of substantially parallel rays from the source 10. 70

Located in the path of the beam 13 is a glass screen 12 which is adapted to elongate the beam and to cause its intensity to vary progressively from a comparatively high value adjacent one end to a comparatively 75 low value adjacent the other. As here shown, this screen comprises a plurality of parallel prismatic corrugations 14, 14^a, 14^b, 14^c, 14^d, 14^e, 14^f, 14^g, which corrugations I will hereinafter refer to as "prisms." The 80 rays 13 which reach each prism are, of course, refracted thereby so that on emerging from the prism they form a certain angle with the rays 13. The several prisms are so formed that the angle of refraction of each 85 prism is different from that of any other prism, and that this angle progressively increases from prism 14, which causes the least refraction, to prism 14^g, which causes the greatest refraction. These angles of refraction are indicated by the lines 15, 15^a, 15^b, 15^c, 15^d, 15^e, 15^f, 15^g, which represent the 90 direction of the rays emerging from the several prisms, and from which it will be seen the angle increases progressively. Hence, the 95 beam of light projected by the screen is elongated in the direction of line IV—IV. Furthermore, these prisms vary progressively in area from prism 14 the area of which is maximum to prism 14^g the area of which is 100 minimum, hence it will be seen that the intensity of the beam varies progressively from a maximum value adjacent the end corresponding to prism 14 to a minimum value adjacent the other end. This variation of 105 intensity is indicated roughly by the curve in Fig. 4.

The screen 12 shown in Fig. 1 comprising

prisms 14 whose inclined surfaces are flat, so that all the rays emerging from each prism are parallel. From Fig. 3 it will be seen that with this construction the rays 5 emerging from one prism, prism 14^a of Fig. 1, for example, are at an angle to all of the rays emerging from the adjacent prism 14^b, hence in the beam projected from the signal there will be, theoretically at least, a dark 10 strip 16 between the two adjacent strips of light 15^a and 15^b. Similarly, there will be, theoretically at least, a dark strip between the strips of light projected by each two adjacent prisms in Fig. 1. Hence, theoretically 15, the curve shown in Fig. 4 would be broken at intervals by parts which would drop abruptly to the base line. In practice, however, owing to inaccuracies in the surfaces of the lens 11 and screen 12, and owing 20 also to the fact that the filament of lamp 10 cannot be concentrated at the focus of the lens, the rays from adjacent prisms will actually blend together so that there will be no dark strips which can readily be detected 25 by the eye; that is, the intensity of the light will appear to vary smoothly as indicated in Fig. 4.

In Fig. 5 I have shown a railway curve F, at one end of which is a signal S of the 30 type shown in Fig. 1, and which projects a beam varying in intensity substantially as indicated by Fig. 4. Signal S is so located that the portion A of the beam projected by the signal is directed toward section A' 35 of the curve, portion B toward B', etc. That is, the most intense portion of the beam is directed toward the section of the curve farthest from the signal, and the portions of the beam of progressively decreasing 40 intensity are directed toward the sections of the curve progressively approaching the signal. Hence, as an observer passes along the curve F toward the signal, the beam of light is constantly visible, and con- 45 stantly appears of substantially the same intensity. There is, therefore, no light wasted in unnecessarily intense illumination at any one part of the curve.

Although I have herein shown only one 50 form of signal embodying my invention, it is understood that various changes and modifications may be made therein within the scope of the appended claims without departing from the spirit and scope of my in- 55 vention.

Having thus described my invention, what I claim is:

1. A signal adapted for use on a railway curve and comprising a source of light, means for projecting from said source a beam of substantially parallel rays, and a glass screen located in said beam and comprising a series of vertically disposed prisms increasing in angle and decreasing in area from one side of the beam toward the other, 60 said beam-projecting means and said screen being so placed that the portion of the beam which is deflected through the greatest angle is directed toward one end of the curve and the portion of the beam which is deflected 65 through the least angle is directed toward the other end of the curve.

2. A signal adapted for use on a railway curve and comprising a source of light, means for projecting from said source a beam of substantially parallel rays, and a glass screen located in said beam and comprising a series of vertically disposed prisms increasing progressively in angle from one side of the beam toward the other, 75 said beam-projecting means and said screen being so placed that the portion of the beam which is deflected through the greatest angle is directed toward one end of the curve and the portion of the beam which is deflected 80 through the least angle is directed toward the other end of the curve.

3. A signal adapted for use on a railway curve and comprising a source of light, means for projecting from said source a beam of substantially parallel rays, and a glass screen located in said beam and comprising a series of vertically disposed prisms increasing progressively in angle from one side of the beam toward the other, 90 said prisms also decreasing progressively in area from one side of the beam toward the other, said beam projecting means and said screen being so placed that the portion of the beam having the greatest intensity is directed 95 toward the far end of the curve and the portion of the beam having the lowest intensity is directed toward the part of the curve nearest the signal.

In testimony whereof I affix my signature 105 in presence of two witnesses.

ROBERT M. GILSON.
